(57) **CLAIM**

The ornamental design for a computer liner bag as shown and described.

DESCRIPTION

FIG. 1 is a first perspective view of a computer liner bag showing by new design;

FIG. 2 is a second perspective view of thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a first folded state view thereof;

FIG. 10 is a second folded state view thereof;

FIG. 11 is an enlarged view of the encircled area 11 in FIG. 1;

FIG. 12 is an enlarged view of the encircled area 12 in FIG. 3;

FIG. 13 is an enlarged view of the encircled area 13 in FIG. 5;

FIG. 14 is an enlarged view of the encircled area 14 in FIG. 7; and,

FIG. 15 is an enlarged view of the encircled area 15 in FIG. 8.

The boundary lines in FIGS. 1, 3, 5, 7 and 8 show the areas that are enlarged and broken away in FIGS. 11, 12, 13, 14 and 15. These boundary lines from no part of the claim.

1 Claim, 15 Drawing Sheets
